OVEN

Robert G. Wilson, 643 E. Faris Road,
Greenville, S.C. 29605

Filed Aug. 3, 1964, Ser No. 81,145

Term of patent 14 years

(Cl. D81—10)

Fig. 1.

Fig. 4.

Fig. 2.

Fig. 5.

The dominant features of my design reside in the portions shown in full lines.

I claim:

The ornamental design for an oven, substantially as shown and described.
